UNITED STATES PATENT OFFICE.

ARTHUR F. BENNETT, OF RICHMOND HILL, NEW YORK, AND CHARLES R. MOORE, OF MAPLEWOOD, NEW JERSEY, ASSIGNORS TO WESTERN ELECTRIC COMPANY, INCORPORATED, OF NEW YORK, N. Y., A CORPORATION OF NEW YORK.

INTELLIGENCE SIGNALING APPARATUS.

Application filed August 20, 1925. Serial No. 51,278.

This invention relates to telephone transmitters and more specifically to a transmitter which is particularly well adapted for use in telephone hand sets.

5 For maximum transmission efficiency hand sets of the types heretofore used required that the hand set be maintained while in operation in a substantially vertical position with a very limited range on each side 10 of the vertical. The operative position of the set was determined by the type and the disposition of the microphone in the transmitter, and any deviation from this limited 15 range when, for example, the user moves the hand set too far from the vertical position, greatly interferes with the transmission of speech. This is due to the fact that when the set is held in certain positions a part of the carbon granules move out of 20 contact with the plunger with the result that the carbon is not fully acted on by the vibrations of the plunger, thus impairing the transmission of speech.

Transmitters made according to this 25 invention entirely avoid these defects by the use of a novel arrangement of parts whereby the hand set may be used in practically any position without interfering in any way with efficient and clear transmission of 30 speech, and which will in general greatly improve the quality of the transmitter in the transmission of speech or other signals.

This and other advantages of this invention will appear from the following description 35 and by the claims appended thereto, reference being had to the accompanying drawings in which Fig. 1 is a side assembly view of a telephone hand set;

Fig. 2 is a front view thereof; and

40 Fig. 3 is an enlarged sectional view of the transmitter embodying the features of this invention.

Signaling apparatus to which this invention is particularly well adapted for use, 45 generally consist of a handle 9, at the ends of which a receiver unit 10 and a transmitter 11 are mounted. The transmitter unit made according to the features of this invention consists of a metallic shell 12 provided with 50 a partition 13 disposed in a manner to form two inverted bell portions E and B. The rim of bell portion E is inwardly threaded and fits a metallic flange which extends perpendicularly from a base of the handle 9.

A microphone is mounted in the bell portion 55 B and comprises a conical shaped diaphragm 14, the base of which is adapted to rest between damping rings 15 and 16 mounted in a recess made by the provision of a cylindrical flange in a mounting plate 17. This 60 plate has a plurality of radially disposed apertures such as 18 and 19, shown in Fig. 3 which have been provided for a purpose that will be hereinafter described. In the central portion of plate 17 there is provided 65 a centrally disposed recess in which a pad of thin paper rings 21 is held in position concentric with respect to a central opening in the plate 17 and in engageable relation with a truncated portion of diaphragm 14 70 with which the pad of paper rings 21 cooperates to form a closure for the carbon granules 22. The disc 17 is provided with a central opening 20, the bounding surface 75 of which contacts with the carbon granule and forms the innermost disposed electrode of the microphone. A cylindrical flange portion 20' of disc 17 is inwardly and outwardly threaded. The inwardly threaded portion of this flange is adapted to receive 80 the outermost disposed electrode 24 which is insulated therefrom by means of a flanged insulating ring 26, held in adjusted position therein by means of a metallic ring 27, screwed into the inwardly threaded portion 85 of disc 17. A plate ring 23 of insulating material is disposed between the electrodes 20 and 24 in order to form therewith a microphone of the barrier type. A disc member 28 has a threaded engagement with 90 electrode 24 and serves in cooperation with the insulating disc 24' to form the outwardly disposed wall for the microphone. On the disc 28 is rigidly secured a double armed contacting member 35 the arms of which extend radially in opposite directions in the slots of a ring 29 with which they contact through the medium of their own tension. Ring 29 serves for holding an oiled silk screen 44 and an aperture frame 45 together 95 with the plate 17 in adjusted position in the bell portion B of the shell 12 and is insulated from apertured frame 45 by means of ring 36.

A mouthpiece 30 is adapted to be screwed 105 tightly on the periphery of the bell portion B and in it a sound deflecting member 31 is mounted. This sound deflecting member

is disposed adjacent the opening of the mouthpiece and is adapted to cooperate therewith to form an annular air passage. The metallic screen 32 and the sound deflecting member 31 are held in the mouthpiece by means of an apertured ring 33 which like the transmitter mouthpiece may be made of any suitable insulating material. A metallic ring 34 adjacently mounted at the base of 10 the diaphragm 14 but separated therefrom by the pad of damping rings 15 and insulated from the shell 12, by means of insulating strip 40 and ring 37 has a radial arm 38 which extends in engageable relation with 15 a tightening screw 39. This screw is insulated from the partition 13 and is provided for holding the contacting spring 46 in electrical connection with the electrode 20 and the associated connection in the handle 20 through the mounting plate 17 thus forming one side of the microphone electrical circuit. The other side of the microphone circuit being through the resistance varying material in contact with electrode 20, electrode 25 24, disc 28, the double armed member 35, the slotted ring 29 and the transmitter shell 12 having suitable connection with the incoming wire 47 and the electrical part in the receiver 10.

30 By means of this arrangement the sound waves are deflected in the annular path formed by the conical member 31 and the mouth piece 30 through the metallic screen 32, the apertured ring 33, the apertured 35 frame 45 supporting the oiled silk screen 44, the screen, and thence through the apertures 18, 19, etc. of mounting plate 17 to one side of the diaphragm 14. But it is to be noted that the initial displacement of the dia- 40 phragm is in a direction away from the resistance varying material in the microphone which greatly improves the transmission and efficiency of the transmitter. By means of this construction the hand set may be held 45 in any position without danger of breaking the electrical circuit of the microphone since the resistance varying material will in any position continue to bridge the two electrodes 20 and 24 through the barrier 23 and 50 due to the resistance varying material resting on the diaphragm any sound wave impressed thereon through the air paths above traced will be faithfully reproduced at the receiver end of the line thus avoiding all the 55 inconveniences present in telephone hand sets now in use.

The transmitter mouth piece 30 may be held in adjusted position with respect to the longitudinal axis of the handle by means of 60 a lock nut 43 which is screwed on the periphery of the rim bounding the bell portion E in abutment with the base of the handle as shown.

What is claimed is:

65 1. A telephone transmitter comprising a

granular electrode chamber, a pair of stationary electrodes insulated from each other and forming the marginal walls of said chamber, a stationary front wall forming an insulated closure for said chamber, and a 70 diaphragm the central area of which forms a closure for the rear of said chamber.

2. A telephone transmitter comprising a granular electrode chamber, a pair of stationary electrodes insulated from each other 75 and forming the marginal walls of said chamber, a stationary front wall forming an insulated closure for said chamber, and a diaphragm the central area of which forms a closure for the rear of said chamber, the 80 peripheral part of the same side of the diaphragm which engages the granular material communicating with an air passage leading to the transmitter mouthpiece.

3. A transmitter comprising a metallic 85 shell, a conical shaped diaphragm resiliently held in adjusted position therein, a microphone element containing resistance varying material actuated by said diaphragm, a mouthpiece, a sound deflecting device there- 90 in forming an annular air passage leading the pressure waves in a direction for operating said diaphragm away from said material.

4. A transmitter comprising a microphone 95 having resistance varying material therein, coaxially disposed electrodes forming the marginal walls of said microphone, a dia- phragm in contacting relation with said ma- 100 terial, a rigid insulating disc forming a closure of the microphone, a metallic shell for supporting said diaphragm and said electrodes in position concentric with respect to each other, a mouthpiece in threaded en- gagement with the periphery of said shell, 105 a sound deflecting device cooperating with said mouthpiece whereby the displacement of the diaphragm in response to pressure waves impinged on one side thereof at its peripheral portion is effected in a direction 110 away from the resistance varying material.

5. A transmitter comprising a metallic shell, a microphone mounted in said shell, said microphone comprising co-axially dis- 115 posed electrodes forming the marginal wall of the chamber containing the resistance varying material, an insulating member dis- posed between said electrodes, a rigid mem- ber secured to one side of said electrode and forming a side wall for said chamber, a dia- phragm forming the other wall of said chamber, a mouthpiece for housing said mi- 120 crophone, and a sound deflecting device co- operating with said mouthpiece to form an annular air path for operating said dia- phragm to loosen said material upon the impinging of pressure waves on one side of the diaphragm.

6. In a transmitter, a mouthpiece, a mi- 125 crophone having co-axial electrodes forming 130

- the marginal walls of the granule chamber, carbon granules in said chamber, a diaphragm disposed in contacting relation with the carbon granules and adapted to form 5 the rear wall of said chamber, a solid disc having one of its plane surfaces insulated from the carbon and adapted to form the front wall of said chamber, and a contacting device secured to said disc adapted to form 10 one terminal of the microphone circuit.
7. In a transmitter, a supporting metallic shell having a central partition, a microphone mounted on one side of said partition, a diaphragm disposed adjacently to said 15 partition and arranged to form a wall for the microphone, a plurality of damping rings associated with said diaphragm for holding the resistance varying material in said microphone, a mouthpiece secured to 20 the periphery of said shell, a sound deflecting device in said mouthpiece adjacent the opening of said mouthpiece and forming an annular air passage for actuating said microphone upon the impinging of pressure 25 waves on the peripheral portion of said diaphragm.
8. In a transmitter, a microphone having resistance varying material and a diaphragm arranged to form a wall for the microphone, a plurality of damping rings associated with said diaphragm for holding the resistance varying material in said microphone, a plurality of damping rings disposed at the periphery of said diaphragm, 30 a mouthpiece for said transmitter, and a sound deflecting device cooperating with the mouthpiece for causing the movement of 35
- said diaphragm to increase the electrical resistance of the microphone in response to pressure waves impinged on one side and at 40 the peripheral portion of said diaphragm.
9. In a transmitter, a mouthpiece, a barrier microphone having a solid wall adjacent said mouthpiece, resistance varying material in said microphone, a conical diaphragm having its apex in contacting relation with said material, a sound deflecting device co-operating with the mouthpiece to form an annular air path leading to the periphery of said diaphragm and a plurality of screen 50 protectors across said air path.
10. A transmitter mounting having a threaded flange extending perpendicularly to the base of the mounting, the transmitter having a mouth piece, a shell having threaded portions for engaging said flange and the mouth piece, and a screw threaded ring of insulating material engaging said shell for securing said mouth piece in adjusted position with respect to the mounting. 55
11. A telephone transmitter comprising a granular electrode chamber, a pair of stationary electrodes insulated from each other and forming the marginal walls of said chamber, one of said electrodes having a central portion forming the front supporting wall of said chamber, and a diaphragm the central area of which forms a closure for the rear of said chamber. 60
- In witness whereof, we hereunto subscribe 70 our names this 7th day of August A. D., 1925.

ARTHUR F. BENNETT.
